(57) **CLAIM**

The ornamental design for a combined wheel well cowling and safety guard, as shown and described.

DESCRIPTION

FIG. 1 is a perspective view of a combined wheel well cowling and safety guard according to my design shown for possible mounting on a school bus;

FIG. 2 is a front elevational view of the combined wheel well cowling and safety guard of FIG. 1;

FIG. 3 is a left side view of the wheel well covering safety guard of FIGS. 1 and 2; and,

FIG. 4 is a top view of the combined wheel well cowling and safety guard according to the invention.

The broken lines in FIG. 1 showing an outline of a school bus is for illustrative purposes only and forms no part of the claimed invention. In addition, no aspects of the invention are associated with the left, bottom or rear side views of the combined wheel well cowling and safety guard.
